CENTRIFUGAL CASTING MECHANISM

Filed July 27, 1923 5 Sheets-Sheet 5

UNITED STATES PATENT OFFICE.

ARTHUR E. PAIGE, OF PHILADELPHIA, PENNSYLVANIA.

CENTRIFUGAL CASTING MECHANISM.

Application filed July 27, 1923. Serial No. 654,231.

To all whom it may concern:

Be it known that I, ARTHUR E. PAIGE, a citizen of the United States, residing at Philadelphia, in the county of Philadelphia and State of Pennsylvania, have invented a certain new and useful Improvement in Centrifugal Casting Mechanism, whereof the following is a specification, reference being had to the accompanying drawings.

As hereinafter described; my invention may be employed with particular advantage in the manufacture of iron pipes, by what are known as "centrifugal processes". In such processes, a cylindrical mold is rotated while molten iron is poured therein, so that the socalled centrifugal force which rotation develops in a revolving mass causes the molten iron to distribute itself in an annular shell on the inside of the rotating mold. Pipe thus cast is of much denser composition and far more resistant to stresses than pipe cast in ordinary sand molds. Consequently, it is possible to use centrifugally cast pipe of less thickness than sand cast pipe to resist the same stresses. However, ordinary sand molds have cores which predetermine the thickness of the pipe cast therein, whereas, as it is impossible to employ such cores in centrifugal molds, it has heretofore been impossible to precisely predetermine the thickness of centrifugally cast pipe; the thickness thereof being determined, with more or less irregularity, solely by the judgment of the operators, either as to the volume or as to the rate of introduction of the molten metal poured into such rotary molds. Consequently, the advantages of employing such centrifugal processes are lessened by the irregularity in thickness of the pipes thus produced.

Such centrifugal pipe casting apparatus as has been used commercially, has been of two types, to wit, first, that in which the axis of the rotary mold is maintained horizontal and the metal poured into the same simultaneously throughout the length of the mold, from a tiltable trough extending within the mold and in which the volumetric quantity of metal to be poured is determined by visual inspection and judgment of the operator. Such mechanism has been discarded and superseded by the second type of mechanism wherein the mold is maintained with its axis inclined to the horizon and the metal is poured therein beginning at the lower end of the mold and continuing to-

ward the upper end of the mold, from a trough extending in and relatively axially movable in the mold; either by holding the mold stationary axially and shifting the trough, or by holding the trough stationary axially and shifting the mold.

In the latter type of mechanism, there are at least five variable factors which determine the thickness of the pipe, viz., first, the angle of inclination of the mold; second, the temperature of the iron at the moment it is cast; third, the rate of flow of the metal from the delivery end of the trough into the mold; fourth, the rate of rotation of the mold; and, fifth, the rate of longitudinal traverse of the trough relative to the mold. Of course, the first factor aforesaid may be fixed and the second may be controlled within a sufficiently limited range. However, each of the third, fourth and fifth factors aforesaid is, in accordance with the present practice, determined independently of the other and by the judgment of the different operators; with the result that in one run with the same gang of men and the same machine, casting nominal six inch diameter pipes, the weight of the latter ranged from two hundred and fifty-four to three hundred and seventy-two pounds; the lightest pipe being nine thirty-seconds of an inch thick and the heaviest seven sixteenths of an inch thick.

Therefore, it is an object and effect of my invention to provide means which are substantially automatically operative, to precisely predetermine the thickness of centrifugally cast pipe by coordination of the means for controlling the third, fourth and fifth factors aforesaid, and thus enable the manufacturer to produce pipe of uniform thickness and avoid the losses incident to the irregularities aforesaid.

Moreover, in accordance with the prior art construction and practice, with mechanism of the most compact form of the second type aforesaid; the cast pipes are discharged from the mold by a device which, at the conclusion of the casting operation, grasps the end of the pipe initially cast and pulls it axially from the mold, with an outrigger which occupies a floor space more than the length of the pipe; so that the total floor space occupied by a casting mechanism of that type, including space for the relative longitudinal movement of the mold and trough, is more than three times the length

of the pipe. Therefore, a further object and effect of my invention is to dispense with the grappling outrigging and effect the discharge of the cast pipe by the relative movement of the mold and trough, by providing the latter with an abutment ring which first limits the extent of the pipe in the mold, during the casting operation, and thereafter serves to push the pipe out during the relative return movement of the mold and trough to their initial casting position. Incidentally; such construction and arrangement of my invention save the time and labor of manipulating the grappling device aforesaid.

In the form of my invention hereinafter described; the mold is maintained axially stationary and the pouring trough is automatically reciprocated axially therein by rigidly connecting the outer end of said trough with a screw which is mounted to reciprocate beneath the mold and is reciprocated by rotation of a nut thereon; without axial movement of the nut.

Furthermore, the rotary molds of the prior art have been formed with massive walls of ferric metal, and the present commercial practice was to use, at first, cast iron, and thereafter cast steel. However, it is the present practice to employ molds formed entirely of solid unitary nickel steel forgings finished upon their interior surfaces by boring operations. Such molds must be massive enough to withstand the strains which tend to distort the various parts of their bores from coaxial relation and, consequently, are several inches thick. Despite the fact that the present cost of wrought nickel steel is fifty cents per pound and the cost of such molds averages five dollars per ton of nominal six inch diameter water pressure pipes of standard dimensions cast therein; such molds have been found to be more economical than the prior art molds cast solidly of iron or steel; for the reason that such nickel steel is more durable under the stresses incident to the rapid and extreme changes in temperature to which such molds are subjected, incident to the application of molten iron upon their interior surfaces, while their exterior surfaces are in contact with cold water. The ultimate effect of the irregular contraction and expansion incident to such stresses is to produce inner surface cracks in transverse relation like irregular mosaic divisions, and thus ultimately render the interior of the molds so rough and irregular that the castings cannot be withdrawn therefrom. When such a mold thus deteriorates,

of course, its entire mass must be scrapped and, therefore, as aforesaid, the cost of such molds averages five dollars per ton of the pipes cast therein. Therefore, an adjunctive feature of my invention is the provision of a mold of an entirely different type;

designed to minimize both the initial cost of production of the molds and the continuing cost of maintenance thereof.

As hereinafter described; my improved molds are formed of comparatively thin shells of ferric metal of the kind ordinarily employed for boiler tubes and commercially obtainable at minimum cost in suitable cylindrical forms and sizes; thus eliminating the necessity for boring or otherwise machining their inner surfaces. Of course, such a mold deteriorates and must be ultimately scrapped but the mass of the metal therein and the cost thereof are at the minimum, and the construction and arrangement of the means for cooling such molds are such as to facilitate and minimize the cost of the removal and the replacement of such molds with respect thereto.

As hereinafter described, such cooling means includes a water tank which is held stationary and in which the mold rotates with practically the entire outer surface of the mold exposed to the water in the tank; so that the temperature of the mold is maintained below that at which the molds of the prior art are subjected to distortion from axial alinement.

My invention includes the various no features of construction and arrangement hereinafter more definitely specified.

In said drawings; Fig. I is an elevation of the right hand side of a centrifugal casting mechanism embodying my invention. Fig. II is a front end elevation of said mechanism as seen from the left of Fig. I, but on a larger scale than the latter. Fig. III is a fragmentary vertical longitudinal sectional view of said mechanism, taken on the line III, III in Fig. II. Fig. IV is a fragmentary vertical sectional view, similar to Fig. III, but on a larger scale, and showing the pouring ladle and shoot for directing the molten metal into the mold and means for automatically tilting said ladle. Fig. V is a plan view of said pouring ladle and shoot. Fig. VI is a fragmentary partly sectional rear view of said tilting mechanism, showing the adjustable tripping mechanism, arranged to automatically initiate the longitudinal movement of the pouring trough. Fig. VII is a cross sectional view of the pouring trough, taken on the line VII, VII in Fig. III.

In said figures; the base frame 1 is conveniently formed of wrought steel, including two opposite longitudinally extending channels 2, connected by four cross channels respectively 3, 4, 5 and 6, in rigid rectangular relation with said channels 2. The opposite end cross channels 5 and 6 of said frame 1 each support two roller bearing brackets, all four of which are alike, but the brackets on said frame member 5 are marked 8 and those on said frame member

6 are indicated at 9. Said brackets 8 and 9 support two shafts 10 which are conveniently held stationary and support four mold bearing rollers which are all alike, but 5 the two at the front end of the machine are marked 12 and the two at the rear end of the machine are marked 13. Said frame 1 and rollers 12 and 13 support the rotary mold 15, which has the annular bearing 10 flange 16 at its front end engaging said rollers 12, and has the annular flange 18 at its rear end engaging said rollers 13.

Said mold is conveniently formed of a cut 15 length of cylindrical commercial boiler tubing 20 to which the pressed sheet metal bell end member 21 is rigidly connected, conveniently by the annular welded joint 22 and spot welds 23.

In order to form the pipe 25 with an 20 interior diameter at its bell end larger than the cylindrical portion of the pipe; I provide said mold with a tubular core 26, conveniently formed of cementitious material, carried by the metallic core tube 27, which 25 is also conveniently formed of pressed sheet metal and removably fitted in said bell member 21 of the mold. As hereinafter described, said core is designed to be automatically pushed out by the cast pipe 25 30 when the latter is discharged from the mold; but said core is thereafter manually replaced. Therefore, I find it convenient to provide said bell mold member with a conical zone 28 to fit a corresponding conical zone 29 on said core tube so that the latter may be readily removed and replaced in the proper position without waste of time of the operator to determine the same.

In order to prevent distortion of said 40 mold; I provide means to subject it to the action of the refrigerating fluid 30, preferably water, and conveniently by surrounding said mold with the stationary tank 31 held in coaxial relation therewith by two frame brackets 32, each having three set screws 33. Said tank has the cold water inlet 34 at the bottom thereof and the hot water outlet 35 at the top thereof respectively connected with a cold water supply, 45 under pressure, and with a drain. In order to permit rotation of said mold in said tank without leakage of the water; I provide the front end of the tank with rings of packing 36 in a suitable stuffing box 38 provided 50 with the adjustable gland 39, and provide the rear end of said tank with the packing rings 41 in the stuffing box 42 provided with the adjustable gland 43.

It is to be understood that the circulation 60 of water through said tank may be controlled by controlling the passage of water into the cold water inlet aforesaid or by controlling the passage of water from the hot water outlet. In either case, the water flows 65 upwardly through the tank and the mold is

continuously rotated therein during the casting operation so as to maintain the mold at the proper predetermined temperature.

The molten metal is directed into said mold by way of the pouring trough 45, 70 which is conveniently formed of a half section of standard wrought iron pipe 46 lined with removable cast iron trough blocks 47. In order to maintain said trough at the proper temperature to prevent the molten metal from sticking to it; I prefer to subject it to the action of a refrigerating material, preferably tap water, by means of pairs of pipes 49 and 50 which extend in the trough beneath said blocks, in telescoped 80 relation. Cold water is directed through the inner pipes 49 through the detachable union fittings 51 at the outer end of the trough and returns in the space between said inner pipes 49 and the outer pipes 50 and is 85 discharged through the detachable union fittings 52. Said fittings 51 and 52 may be conveniently provided with flexible hose connections 54 and 55 respectively leading to a water supply pipe and to a drain. 90

Said trough 45 has, at its outer end, the yoke 57 rigidly connecting it with the screw shaft 58 by which it is reciprocated, and said trough rests upon and is guided by the idle roller 60 supported by the shaft 61, upheld by the stationary frame bearing brackets 62. Said screw shaft 58 is conveniently provided with two threads 63 of half inch pitch and is arranged to be axially reciprocated by the nut 64 which is 100 mounted to rotate, without axial movement, in the roller bearings 65 and 66; the former being mounted directly in the stationary frame member 68, and said bearing 66 being mounted in coaxial relation therewith, 105 in the frame member 69, which is detachably rigidly connected with said frame member 68. The length of the traverse of said trough 45 is, of course, predetermined by the length of said screw shaft 58 which is provided with said threads 63. However, the length of such traverse is the length of such threaded portion of said shaft 58 plus the length of said nut 64. That is to say; 110 during the normal operation of the machine; said shaft 58 reciprocates through said nut and comes to rest at each end of its traverse when said nut runs off the threads 63 onto the unthreaded portion of said shaft 58. Said threads being right hand; such traverse of said trough 45 and shaft 58 is effected outward, with reference to the mold, when said nut is rotated clockwise as seen 115 from the front of the machine, and inward movement of said shaft and trough are effected by reverse rotation of said nut. To insure engagement of said threads 63 with said nut 64 to initiate such movement in either direction; I provide said shaft 58 120 with the spring 70 and thrust collar 71, at

its outer end; said spring being so proportioned as to tend to draw said shaft through the nut when the latter runs off the screw thread 63 at that end. Similarly, I provide 5 the inner end of said shaft 58 with the spring 73 and thrust collar 74, said spring being held in the proper position, by the abutment collar 75, which is detachably rigidly connected with said shaft 58, conveniently by the tapered pin 76, so that said 10 spring tends to draw said shaft through said nut when the latter runs off said threads 63 at the inner end of said shaft. Said shaft 58 reciprocates in the guide tube 77, which 15 is rigidly supported in said frame member 69 and in the bracket 78.

The above described rotary movements of 20 said nut 64 are conveniently effected by rigidly connecting therewith the gear 79, between said roller bearings 65 and 66, in engagement with the gear 80 on said annular bearing flange 16; so that the longitudinal movement of said trough 45 is effected in 25 definite predetermined cooperative relation with the rotation of said mold 15; regardless of how the latter is rotated.

However, I find it convenient to rotate 30 said mold by the gear 81 which is journaled on the bracket 82 rigidly connected with the frame platform 83. Said gear 81 is conveniently driven by the gear 85 on the rotor shaft 86 of the electric motor 87 which is rigidly connected with said platform 83.

The construction and arrangement above 35 described are such that when said motor is operated to rotate said driving gear 85 clockwise, when seen from the front of the machine, said trough 45 is shifted into the mold until the nut 64 runs off the screw 40 threads 63 at the outer end of said shaft 58; so that further rotation of said motor, in the same direction, merely effects continued rotation of the mold, in the same direction, without movement of the trough. However, 45 upon reversal of the direction of rotation of said motor 87; said spring 70, at the outer end of said screw shaft 58, would cause said shaft to instantly begin to move outward, with said trough 45, if said spring be then 50 free to act. Therefore, I arrange to variably determine the instant of beginning of such outward movement of the trough, during which the metal for the casting is 55 poured in the mold, by controlling the action of said spring 70. The mechanism for effecting such control includes the detent lever 89, which is arranged to automatically snap into engagement with the outer end of said yoke 57, at the lower end thereof, at the 60 instant said nut 64 runs off said threads 63 at the outer end of said screw shaft 58, i. e., at the instant said trough 45 reaches the inner limit of its movement. Said detent lever is fulcrumed upon the axis of the shaft 65 90 which is mounted to rock in the bearings

91 in said stationary frame member 68. I provide means to automatically release said detent lever and thus initiate the outward movement of said trough 45 at a predetermined but adjustably variable instant in the 70 pouring operation, by the means herein-after described, for tilting the pouring ladle 93.

Said pouring ladle 93 is mounted to rock 75 upon the axis of the shaft 94, which is conveniently rigidly connected therewith, and journaled in the bearings 95 in the stationary frame member 96, which is detachably rigidly connected with the top of the stationary shoot 98, through which the molten 80 metal 99 is directed into said trough 45. As indicated; said trough and shoot may be lined with removable cementitious material 100. Said shoot should be so curved as to afford the maximum gravitational acceleration 85 to the molten metal.

Said ladle has the undercut channel member 101 conveniently detachably rigidly connected therewith by the screws 102, to engage, in variable radial position with respect to the axis of oscillation of the ladle, the link pivot 103 which has the base slide block 104 which is adapted to be adjusted longitudinally in said channel 101 and be rigidly connected therewith in adjusted position, by the set screw 105. Said pivot 103 is engaged by the upper end of the link 107 which has its lower end engaged with the pivot 108 on the sleeve 109 which encircles the ladle lift screw shaft 110 and is vertically adjustable thereon by the lock nuts 111 engaging the screw thread 112.

Said ladle lift screw shaft 110 is provided with means hereinafter described adapted to reciprocate it automatically to a predetermined invariable extent, for instance, three inches; and the above described adjustable pivotal connections for said link 107 are provided to enable the operator to adjustably and variably determine the position of the ladle at which it begins to pour the molten metal 99 down said shoot 98, and the angular movement of said ladle consequent upon the vertical movement of said lift screw shaft 110. Such angular movement determines the volume of metal poured, and the arrangement is such that such pouring movement of the ladle may be coextensive with the longitudinal movement of the trough, outward, or more, or less; in accordance with such adjustment.

That is to say; said ladle 93 must be tilted to different extents in accordance with the volume of molten metal 99 which it is desired to deliver into the mold for a given casting, and it is desirable to have such delivery effected uniformly during the entire traverse of the trough 45, and the adjustable elements aforesaid permit variation in the amount of metal poured from the ladle per 120 125 130

unit of traverse of the trough; despite the fact that the range of movement of the ladle lift screw shaft 110 is invariable.

Said ladle lift screw shaft 110 is mounted to reciprocate in two stationary bearings, viz., the step bearing 114 (which is part of said base frame member 68), and the top bearing 115 which is rigidly connected with the frame member 117. Said shaft is prevented from turning by engagement of its keyway 118 with the key 119 in said top bearing 115. Said shaft 110 is provided with the ladle lift screw 120 for engagement with the nut 121, by rotation of which it is raised and lowered. In its idle position, shown in Fig. IV, said lift screw shaft 110 rests upon the bottom of said step bearing 114, which thus supports the weight of the ladle, and in that position, said nut 121 encircles said shaft 110 above said screw thread 120; which position said nut has assumed by left hand rotation. However, said step bearing 114 has the socket 123 containing the ball thrust bearing 124 upon which said nut 121 rests when said shaft 110 is lifting said ladle, and said nut 121 comes down upon said bearing and into engagement with said screw thread 120 as the consequence of right hand rotation of said nut; the latter being then pressed downward by the spring 126, which encircles said shaft 110 and has its upper end against the abutment ring 127.

I find it convenient to impart such right and left hand rotation to said nut 121 by providing it with worm gear teeth 128 in engagement with the worm 130 which is rigidly connected with the nut 64 on the trough shifting screw shaft 58 above described.

Of course, the rotary movement of said nut 121 and the axial movement of said ladle lift screw shaft 110 which it effects, are thus coordinated with the rotary movement of said mold which thus effects rotation of both said nuts 64 and 121.

The means arranged to automatically release said detent lever 89 and thus initiate the outward movement of said trough 45 at a predetermined but adjustably variable instant in the pouring operation, include the sleeve 132, shown in Figs. IV, and VI encircling said lift screw shaft 110, upon which it is presented from turning by the key 134 engaging said keyway 118 in said shaft. Said sleeve 132 has the radial pivot stud 135 engaging the upper section of the connecting rod 136 which is rigidly adjustably connected with its lower section by the turnbuckle 137 and jam nuts 138. The lower section of said connecting rod 136 is pivotally connected, by the bolt 139, with the link 140, which latter is pivotally connected with the stud 141 on the arm 142 of said detent lever 89. Said link 140 may be omitted and said rod 136 be directly con-

nected to said arm 142, if the latter be long enough to permit the movement of said sleeve 132. Said sleeve 132 is continually pressed downward by the spring 143 encircling said screw shaft 110, to snap said lever 89 into engagement with said yoke 57. However, said sleeve 132 is lifted to release said detent lever 89 by the upward movement of said sleeve 109, as the latter is raised by said screw shaft 110, consequent upon the rotation of said nuts 64 and 121, and the instant of such release may be adjustably predetermined by the length to which said connecting rod 136 is adjusted. That is to say; said connecting rod may be adjusted to uphold said sleeve 132 above said sleeve 109 to any extent which it is desired to permit said ladle to be lifted, in pouring operation, before said sleeve 132 is lifted to initiate the outward movement of said trough. Such adjustment is so effected that sufficient metal is initially poured into the mold to properly form the bell end of said pipe 25, in said bell member 21 of the mold, before said trough 45 is withdrawn therefrom to the left in Fig. III.

The mechanism above described may be operated as follows: Said trough 45 being at the inner limit of its longitudinal movement with respect to the mold bell member 21, and with said detent lever 89 snapped up into engagement with the outer end of said yoke 57; said motor 87 is started to rotate its driving gear 85 counter-clockwise, as seen from the front of the machine; thus rotating the mold 15, counter-clockwise, and rotating said nuts 64 and 121 clockwise. It said detent lever 89 were released, such movement would initiate the outward longitudinal movement of said trough 45 simultaneously with the upward tilting movement of said ladle 93. However, as said lever 89 is in position to detain said spring 70 from effecting engagement of the screw threads 63 on the screw shaft 68 with said nut 64, the latter rotates idly on said screw shaft 58 but, of course, turns the worm 130 which operates the nut 121 to lift the screw shaft 110 and ladle 93 and initiate the pouring operation of the latter. Such pouring operation of the ladle continues until the sleeve 109 on said 110 picks up the sleeve 132 on said shaft far enough to trip and release said detent lever from engagement with said yoke. Thereupon, said spring 70 draws said screw shaft 58 toward the left in Fig. III, to engage its threads 63 with said nut 64 and continued rotation of the latter, in the same direction, i. e., clockwise, causes the trough 45 to be withdrawn to the left, thus distributing the poured metal throughout the cylindrical portion of the mold 20 until the threads 63 on said screw shaft 58 pass entirely through said nut 64 and the latter turns idly on said

shaft 58 against said spring 73, at the inner end of said screw shaft 58. In that position; the outer end of said pipe 25 is cast against the abutment ring 145 which slip fits the interior of said mold member 20 and is detachably rigidly connected with said trough 45, conveniently by three pins 146, which are driven into engagement with holes in said trough through said ring 145; so that said ring 145 may be removed when worn and replaced by another.

Of course, said ladle lift screw shaft 110 continues to lift said ladle 93 until said nut 121 runs off said screw 120 onto the unthreaded portion of said shaft 110 below said screw. Thereupon, said mold 15, may continue to rotate, in the same counter-clockwise direction, without movement of said trough 45 or ladle 93.

20 However, by reversing said motor 87, so as to drive its gear 85 clockwise, the rotation of said mold is reversed, so that it also turns clockwise, with the result that said spring 73 draws said screw shaft 58 into engagement with the nut 64, then turning counter-clockwise, and initiates the movement of said trough 45 inwardly with respect to the mold and, contemporaneously, reverses the rotation of said nut 121 on the ladle lift screw shaft 110; so that said nut 121 turns to the left, engages said screw 120 which is thrust downwardly therethrough by the weight of the ladle 93, and thus lowers said ladle to its original position. Of course, such inward movement of the trough 45 with respect to the mold member 20 thrusts said abutment ring 145 against the left hand end of the cast pipe 25, shifting the latter axially to the right in 30 Fig. III. Such movement first pushes out the tubular core 26 and its tube 27, from the bell member 21 of the mold, by the movement of said pipe 25; followed by the discharge of said pipe itself as the trough travels to the right in said figure, to assume its initial pouring position.

During such downward movement of the ladle, or at the end of said movement; said ladle may be recharged with molten metal 50 99 and preferably with a weighed quantity thereof. Thereupon, the operation may be repeated as above described.

In the form of my invention above described; I have found it convenient to employ an ordinary commercial electric motor 55 87, making eleven hundred and fifty revolutions per minute, and the gearing connecting the same with said nut 64 is such that the latter rotates at the same rate. The largest gear in that train is carried by the mold and such as to rotate at four hundred seventy-three and a fraction revolutions per minute; which I have found more than sufficient to insure the centrifugal effect desired with respect to pipes up to twelve

inches in diameter. The axial movement of said screw shaft 58 is one hundred and forty-four inches; so that said nut makes two hundred and eighty-eight revolutions to effect such traverse of said shaft 58, in 70 less than sixteen seconds. But, as above described, the detent lever 89 detains the trough from outward movement until after the pouring operation of the ladle has begun. Therefore, the complete casting operation of a standard twelve foot length pipe continues approximately one-half minute. However, all of said movements are so co-ordinated as above described as to effect the cooperation of the various parts of the 80 mechanism automatically. An advantage of such coordination is the elimination of the variations in time of operation of the various parts which are manifested in variations in the product. In other words; such coordination permits uniformity in the pipes produced by reason of uniformity in the operations of producing them. Moreover, in the use of casting machines of the prior art which are not thus automatically operative; anyone of the operators may retard the operation of the mechanism and thus lessen the production of castings, by failing to cooperate with the other operators in the proper rhythm. Therefore, a 95 very important advantage of my invention is that the rhythm of operation may be automatically controlled by the mechanism at the maximum speed of production of which the mechanism is capable. 100

However, as above explained; there are numerous variable factors which affect the operation of centrifugal casting mechanism and the various movements above described must be coordinated in accordance therewith. For instance, in the arrangement chosen for illustration; the axis of the mold is inclined four degrees to a horizontal plane, and the cast iron is poured at approximately 2200° F.; but it is obvious that the angle of inclination of the mold may be different and the metal poured at a different temperature, provided that the other factors are coordinated therewith. 110

Although I have illustrated my invention with reference to mechanism including a mold adapted for casting bell end pipe; it is to be understood that I do not desire to limit myself thereto; as other forms of molds may be employed in interchangeable relation with the other parts of the apparatus above described. 115

Therefore, I do not desire to limit myself to the precise details of construction, arrangement or procedure herein set forth, as it is obvious that various modifications may be made therein without departing from the essential features of my invention, as defined in the appended claims. 125

I claim:

1. In centrifugal casting apparatus, the combination with a rotary mold; of a container arranged to direct molten metal into said mold; and means cooperatively connecting said mold and container; arranged to coordinate effect rotary movements of said mold and container in definite predetermined relation to each other.

2. In centrifugal casting mechanisms, the combination with a rotary mold; of a pouring ladle arranged to deliver molten metal into said mold; and means cooperatively connecting said mold and ladle, arranged to coordinate effect rotary movements of said mold and ladle in definite predetermined relation to each other.

3. In centrifugal casting mechanism, the combination with a rotary mold; of a pouring trough through which molten metal is delivered into said mold; and means cooperatively connecting said mold and trough; arranged to coordinate effect rotary movements of said mold and trough in definite predetermined relation to each other.

4. In centrifugal casting mechanism, the combination with a rotary mold; of a pouring trough arranged to deliver molten metal into said mold; a tiltable ladle arranged to supply molten metal to said trough; and means cooperatively connecting said mold, trough and ladle; arranged to effect rotary movements of said mold, longitudinal movements of said trough with respect to said mold, and tilting movements of said ladle with respect to said trough in definite predetermined relation to each other.

5. In centrifugal casting mechanism, the combination with a rotary mold; of a pouring trough, mounted to reciprocate longitudinally in said mold; and means cooperatively connecting said mold and trough, including a screw rigidly connected with said trough, a nut mounted to rotate in engagement with said screw, without axial movement, and gears connecting said mold and nut; whereby rotary movements of said mold and longitudinal movements of said trough are automatically effected in definite predetermined relation.

6. In centrifugal casting mechanism, the combination with a rotary mold; of a pouring trough, mounted to reciprocate longitudinally in said mold, a tiltable ladle arranged to supply molten metal to said trough; and means cooperatively connecting said mold, trough and ladle, including two nuts, gears operatively connecting said nuts with said mold, and two screws respectively arranged to be engaged and shifted axially by said nuts, one of said screws connected with said trough and the other of said screws connected with said ladle; whereby rotary movements of said mold, longitudinal movements of said trough, and

tilting movements of said ladle are effected in definite predetermined relation to each other.

7. In centrifugal casting mechanism, the combination with a rotary mold; of a tiltable ladle arranged to supply molten metal to said mold; and means cooperatively connecting said mold and ladle, including a screw, having means arranged to prevent it from rotating, a nut mounted to rotate in engagement with said screw, without axial movement, and gears connecting said mold and nut; whereby rotary movements of said mold and tilting movements of said ladle are automatically effected in definite predetermined relation.

8. In centrifugal casting apparatus, the combination with a rotary mold; of a movable container arranged to direct molten metal into said mold; and means cooperatively connecting said mold and container, including a screw, means arranged to prevent said screw from rotating, a nut mounted to rotate in engagement with said screw, without axial movement, and gears connecting said mold and nut; whereby movements of said mold and container are automatically effected in definite predetermined relation.

9. In centrifugal casting mechanism, the combination with a rotary mold; of a pouring trough, mounted to reciprocate longitudinally in said mold; a tiltable ladle arranged to supply molten metal to said trough; and means cooperatively connecting said mold, trough and ladle; arranged to coordinate effect movements thereof in definite predetermined relation to each other.

10. In centrifugal casting mechanism, the combination with a rotary mold; of a pouring trough mounted to reciprocate longitudinally in said mold; a tiltable ladle arranged to supply molten metal to said trough; and means cooperatively connecting said mold, trough and ladle; arranged to effect movements thereof in definite predetermined relation to each other, including a detent device operative to prevent movement of said trough, and tripping means connecting said detent device with said ladle, arranged to release said detent and effect movement of said trough after a predetermined movement of said ladle.

11. In centrifugal casting mechanism, the combination with a rotary mold; of a container arranged to direct molten metal into said mold; means arranged to rotate said mold alternately in opposite directions; means cooperatively connecting said mold and container; arranged to effect movement of said mold and container in definite predetermined relation to each other, including means permitting continued rotation of said mold after predetermined movement of said container contemporaneous with the movement of said mold.

12. In centrifugal casting mechanism, the combination with a rotary mold; of a trough arranged to direct molten metal into said mold; means arranged to rotate said mold alternately in opposite directions; means cooperatively connecting said mold and trough; arranged to effect movement of said mold and trough in definite predetermined relation to each other, including means permitting continued rotation of said mold after predetermined movement of said trough contemporaneous with the movement of said mold.
13. In centrifugal casting mechanism, the combination with a rotary mold; of a ladle arranged to direct molten metal into said mold; means arranged to rotate said mold alternately in opposite directions; means cooperatively connecting said mold and ladle; arranged to effect movement of said mold and ladle in definite predetermined relation to each other, including means permitting continued rotation of said mold after predetermined movement of said ladle contemporaneous with the movement of said mold.
14. In centrifugal casting apparatus, the combination with a rotary mold; of means arranged to direct molten metal into said mold; and means arranged to effect movements of said mold and directing means in definite predetermined relation to each other, including a screw prevented from rotating, and a nut engaging said screw and prevented from axial movement.
15. In centrifugal casting mechanism, the combination with a rotary mold; of a pouring trough, mounted to reciprocate axially in said mold, a tiltable ladle arranged to supply molten metal to said trough; and means cooperatively connecting said mold, trough and ladle, arranged to first effect rotation of said mold for a predetermined interval; then effect contemporaneous rotary movement of said mold and tilting movement of said ladle, and longitudinal movement of said trough, in definite predetermined relation to each other.
16. In centrifugal casting mechanism, the combination with a rotary mold; of a container arranged to direct molten metal into said mold; and means cooperatively connecting said mold and container; arranged to effect movements of said mold and container in definite predetermined relation to each other, including a screw shaft having a screw thread intermediate of its length, and unthreaded portions at each end of said screw thread, and a nut mounted to rotate on said shaft, without axial movement, and springs at respectively opposite ends of said shaft adapted to draw said shaft into engagement with said nut; whereby, rotation of said nut in one direction causes said shaft to move axially therethrough to the extent of said screw thread on said shaft and in said nut and to automatically stop such axial movement with said nut in registry with an unthreaded portion of said shaft and, upon reverse rotation of said nut, cause said shaft to move axially through said nut in the opposite direction, to the extent of the screw thread on said shaft and in said nut, and automatically stop such axial movement with said nut in registry with an unthreaded portion of said shaft.
17. In centrifugal casting apparatus, the combination with a rotary mold; of a container arranged to direct molten metal into said mold; and means cooperatively connecting said mold and container; arranged to effect movements of said mold and container in definite predetermined relation to each other, including an axially movable screw and a nut mounted to rotate on said screw without axial movement; and spring means arranged to automatically engage said screw with said nut at opposite ends of said screw as a consequence of rotary movement of said nut in respectively opposite directions.
18. In centrifugal casting apparatus, the combination with a rotary mold; of a container arranged to direct molten metal into said mold; means arranged to operate said container, including two screw threaded members, in coaxial relation, and means arranged to relatively rotate them.
19. In centrifugal casting apparatus, a rotary mold formed of roll finished wrought ferric metal of uniform thickness and substantially thinner than the castings for which it is designed.
20. In centrifugal casting apparatus, a rotary bell end pipe mold formed of two pieces of roll finished wrought ferric metal substantially thinner than the pipe casting for which it is designed.
21. In centrifugal casting apparatus, a rotary mold formed of wrought ferric metal of uniform thickness and substantially thinner than the castings for which it is designed.
22. In centrifugal casting apparatus, a rotary bell and pipe mold formed of two pieces of wrought ferric metal, each substantially thinner than the pipe casting for which it is designed.
- In testimony whereof, I have hereunto signed my name at Philadelphia, Pennsylvania, this twenty-sixth day of July, 1923.
- ARTHUR E. PAIGE.
